UNITED STATES PATENT OFFICE.

HELEN T. ORR, OF NEWTON, MASSACHUSETTS.

DESIGN FOR A STATUETTE OR EFFIGY OF A DOG.

43,577.

Specification for Design.

Patented Feb. 18, 1913.

Application filed July 1, 1912. Serial No. 707,108. Term of patent 3½ years.

To all whom it may concern:

Be it known that I, HELEN T. ORR, a citizen of the United States, residing at Newton, in the county of Middlesex and Commonwealth of Massachusetts, have invented a new, original, and ornamental Design for a Statuette or Effigy of a Dog, of which the following is a specification, reference being had to the accompanying drawing, forming part thereof.

The figures are (1) a side view (2) a front view of the statuette or effigy, showing my new design.

I claim:

The ornamental design for a statuette or effigy of a dog as shown.

HELEN T. ORR.

Witnesses:

CHARLOTTE P. ORR,
GEORGE K. GARDNER.
